UNITED STATES PATENT OFFICE.

JOHN C. C. HARRIS, OF DANVERS, MASSACHUSETTS, ASSIGNOR TO LOCKE REGULATOR CO., OF SALEM, MASSACHUSETTS, A CORPORATION OF MASSACHUSETTS.

DAMPER REGULATOR.

Application filed September 3, 1924. Serial No. 735,653.

To all whom it may concern:

Be it known that I, JOHN C. C. HARRIS, a citizen of the United States, and a resident of Danvers, in the county of Essex and State 5 of Massachusetts, have invented a new and Improved Damper Regulator, of which the following is a full, clear, and exact description.

This invention relates to damper regulators and more particularly to an improved construction of pressure cap designed for use in connection with apparatus such as disclosed in Patent No. 924,559, granted June 8, 1909, to N. C. Locke.

15 An object of the invention is to provide a pressure cap with an improved construction of post and strut receiving and engaging the scale beam so that the post forms a guide at two sides of the strut engaging opposite sides of the scale beam. This construction will also keep the strut in its proper position and prevent it from being displaced with the downward movement of the diaphragm.

20 With these and other objects in view, the invention consists in certain novel features of construction, and combinations and arrangements of parts which will be more fully hereinafter described and pointed out 25 in the claim.

In the accompanying drawings—

Figure 1 is a view, mainly in elevation, illustrating the apparatus disclosed in the patent above referred to, and in section my 30 improved regulator;

Figure 2 is an enlarged view in section of my improved regulator cap, the view being taken on the line 2—2 of Figure 5;

Figure 3 is a view in section at right angles to Figure 2, the view being taken in section on the line 3—3 of Figure 5;

Figure 4 is a view similar to Figure 3 illustrating a modification;

Figure 5 is a top plan view of the cap 45 illustrated in Figure 2.

1 represents a casing constituting a pressure chamber and communicating directly by steam pipe 2 with a boiler (not shown). This casing 1 is made in two sections secured 50 together by bolts 3, and a diaphragm 4 is securely clamped to the sections of the cas-

ing. 5 represents a scale beam which is fulcrumed as shown at 6 to a portion of the frame 7. On the diaphragm 4 my improved pressure cap 8 is secured and is made with a central vertical post 9 having a strut 10 55 engaging the under face of the beam 5. This cap 6 at the center of its base is formed with a screw-threaded socket 11 to receive a screw 12 projected through the diaphragm to effectually clamp the diaphragm and cap together.

The post 9 above referred to is bifurcated at its upper end so that a pair of upstanding lugs 13 is provided located at opposite sides of the beam 5. The strut 10 above referred to constitutes a knife-edge pin engaging the lower face of the beam 5 and resting in a recess 14 in the post between the lugs 13.

In the form of cap illustrated in Figures 1, 2, 3 and 5, the body portion thereof is of inverted cup-shape, while in Figure 4 the body portion is substantially flat and narrow, as illustrated at 15.

70 The diaphragm 4 is properly shaped to receive the cap and partially enclose the same as indicated in Figure 1, whereas, when a cap such as shown in Figure 4 is employed, a relatively flat diaphragm may be used.

80 The other features illustrated in Figure 1 are common to the construction set forth in the patent above described, and as my invention relates solely to the novel construction and arrangement of pressure cap and its cooperating parts it is needless to describe in detail the construction and operation of the other features, and reference is made to this prior patent to indicate the 85 use of my invention set forth in this application.

To strengthen the construction of the cap and at the same time provide a relatively light cap, I locate in the bottom of the cap a circular series of radial strengthening webs 16.

90 Various slight changes and alterations might be made in the general form of the parts described without departing from my invention, and hence I do not limit myself to the precise details set forth but consider myself at liberty to make such slight 100

changes and alterations as fairly fall within the spirit and scope of the appended claim.

I claim:

- 5 A cap of the character described, comprising a body portion adapted to be fixed to a diaphragm, a central post projecting upwardly from the body portion and having

a bifurcated upper end and having a longitudinal recess in the body portion communicating with the space between the furcations, and a strut located in the recess and having its upper end projected between the furcations and having a knife-edge upper end.

JOHN C. C. HARRIS.
